UNITED STATES PATENT OFFICE.

NETTIE I. E. CURTIS, OF JACKSONVILLE, ILLINOIS.

DESIGN FOR A RUG.

No. 38,224.

Specification for Design.

Patented Sept. 4, 1906.

Application filed May 28, 1906. Serial No. 319,215. Term of patent 3½ years.

To all whom it may concern:

Be it known that I, NETTIE I. E. CURTIS, a citizen of the United States, residing at Jacksonville, in the county of Morgan and State of Illinois, have invented a new, original, and ornamental Design for a Rug, of which the following is a specification, reference being had to the accompanying drawing, forming part thereof.

The figure is a plan view of a rug, showing my new design.

I claim—

The ornamental design for a rug, as shown.

NETTIE I. E. CURTIS.

In presence of—

WILLIAM S. CURTIS,
F. J. CURTIS.
